UNITED STATES PATENT OFFICE.

LARRANCE PAGE, OF BERKELEY, CALIFORNIA.

SHUTTER-RELEASE HOLDER.

Application filed September 14, 1925. Serial No. 56,356.

My invention is a holder for that form of shutter release known as the antinous release or cable release or push-cord release.

In the drawing forming a part of this application, Figure 1 is a front view of the holder, Figure 2 is a side view, Figure 3 is an end view as seen from below when the holder is in the usual position; Figure 4 is a front view of part of a camera front showing the holder in position on the front and also showing the relation of the holder to the release and the shutter; Figure 5 shows one of the two blanks that are used in making the holder.

The holder is made of three pieces of material, two pieces of spring sheet metal or other elastic material and a small machine screw. The two pieces of sheet metal are alike in all respects. The form of one of these is shown in Figure 5. It has a body portion O from which extends two pairs of fingers 1, 1, and 2, 2. These fingers are formed by slots 3 and 4 cut in the metal.

In making the holder these sheet metal blanks are bent, each one at two places shown by the dotted lines in Figure 5. After bending, each piece when seen edge-on takes the approximate form of a capital U, flat on the bottom with one angle a little more than a right angle, the other angle a little less; This is seen best in Figure 2. The upright parts of these capital U's are referred to as the arms when taken entire, but the separate parts formed by slotting the arms are called the fingers. The lower part of the capital U is called the bottom. Two of these U form pieces are placed with their open ends facing each other and then the two are telescoped together so that the long fingers 2 of one pass inside and in contact with the long fingers 2 of the other, and at the same time the short fingers 1 of the second pass inside of and in contact with the short fingers 1 of the first, as seen in Figure 2. These overlapping short fingers 1 form the yoke which holds the two parts of the release together, and by which the release is attached to the camera front, as explained later. In doing this the two long slots 4, 4 register, as do the short slots 3, 3. Then the screw 5 is inserted in the two short slots to clamp the two pieces together. This screw at the same time serves to clamp the holder to the camera front. This is best shown in Figure 2. This figure shows in dotted lines the handle end of the release held in the holder.

The completed holder has roughly the form of a box, with open sides, Figure 2. The form and structure of this box are evident from the way in which it is made. A slot extends the entire length of its top and continues about two thirds the way down through its ends, that is two thirds of the length of the bottom of the U's. The two ends just mentioned are not quite parallel as the box is a little longer at the top than lower down. In other words, the ends are divergent towards the top of the holder. This shape helps hold the release handle. The above-mentioned slot 4 is formed by the overlapping and registering of the slots 4 of the two blanks. Naturally, the long fingers overlap at the same time. These fingers thus close the top of the box.

The holder is adjustable in size to fit large or small releases. This adjustment is carried out by telescoping the two U-pieces more or less, as may be necessary, and clamping them by the screw 5. This adjustment should be such that a moderate pressure is required to insert the release handle, after which the ends of the box spring apart slightly and grip the handle.

It is readily seen that the holder prevents the button of the release 6 from approaching handle proper 7 of the release, that is the roller prevents the release from tripping the shutter. In other words, the holder acts as a lock to the release.

The overlapping long fingers that close the top of the holder (except the slot) prevent either the button or the handle of the release from entering the top of the box, thus aiding materially in placing the release in the holder.

This release holder possesses three improvements over my former holder, as shown in U. S. Letters Patent No. 1,548,481 of August 4, 1925. These are:

1. The closed top.
2. Adjustability to fit any size of release.
3. Improved gripping power of the non-parallel flaring ends.

The terms "long slot" and "short slot" as used here do not necessarily indicate the relative length of the slots, but are terms used to distinguish those slots that extend part way across the bottom of the U-members from those that do not so extend.

I claim:

1. A shutter release holder consisting of two U-shaped members, each of said mem-

- bers having a short slot in one arm and a long slot in the other arm, the said long slots extending part way across the bottoms of said U-members, the open ends of said members telescoping into each other so that the long and short slots of one member register respectively with the long and short slots of the other members, and a clamp screw passing through the two short slots.
10. 2. A shutter release holder consisting of two U-shaped members, each of said members having a short slot in one arm and a long slot in the other arm, the said long slots extending part way across the bottoms of said members, the open ends of said members telescoping into each other so that the long and short slots of one member re-

spectively with the long and short slots of the other member, the bottoms of said members being slightly divergent towards the top 20 of the holder, and a clamp screw passing through the two short slots.

3. A shutter release holder consisting of two U-shaped members, each of said members having a long slot in one arm and a 25 short slot in the other arm, the said long slots extending part way across the bottom of said members, the open ends of said members telescoping into each other so that the long and short slots of one member register 30 respectively with the long and short slots of the other member, and a clamp screw passing through the two short slots.
